UNITED STATES PATENT OFFICE.

LEON F. HOFFMAN, OF FRANKLIN, PENNSYLVANIA, ASSIGNOR TO CHICAGO PNEUMATIC TOOL CO., OF NEW YORK, N. Y., A CORPORATION OF NEW JERSEY.

COORDINATED REGULATING DEVICE.

1,412,805.

Specification of Letters Patent. Patented Apr. 11, 1922.

Application filed February 24, 1921. Serial No. 447,583.

To all whom it may concern:

Be it known that I, LEON F. HOFFMAN, a citizen of the United States, residing at Franklin, in the county of Venango and State of Pennsylvania, have invented certain new and useful Improvements in Coordinated Regulating Devices, of which the following is a specification.

The objects, construction and operation of my coordinated regulating means for an internal combustion engine and an air compressor driven thereby, are herein set forth with sufficient clearness to enable those skilled in the arts to which its construction and operation respectively relate, to make and use the same.

Heretofore, unloading devices for compressors have been commonly employed, and it is not sought to hereby cover such a device in itself, since many of the well-known forms of air compressor unloaders are adapted to be employed in combination in my coordinated regulating means. The unloading device for the air compressor illustrated in the drawings is fully shown and described in Letters Patent of the United States No. 1,224,272, dated May 1, 1917.

In the unloading devices heretofore employed, the operation of the unloader has been confined to the one function of unloading the air compressor when the pressure in the receiver into which the compressor is discharging has reached a predetermined point, but the speed of the internal combustion engine which drives the compressor has been allowed to continue at its normal rate, notwithstanding the fact that it has, for the time being, been relieved of the greater portion of its load.

It is desirable that, when the unloading of a gas-engine-driven air compressor takes place, the speed should be reduced, for the purpose of reducing the wear of the plant to a minimum, also for the sake of economy of fuel, lubricant, and general efficiency. It is therefore one object of this invention to accomplish such speed reduction. Other objects will be presently pointed out.

Certain means whereby I am enabled to accomplish said objects are illustrated in the drawings, which form a part hereof and in which:

Fig. 1 is a diagrammatic elevation of my invention.

Fig. 2 is a central longitudinal section of one end of the actuator valve.

Fig. 3 is a central vertical section of the motive-agent regulating organization for the engine.

Fig. 4 is a central longitudinal section of an inlet valve of an air compressor and an unloading device therefor.

Fig. 5 is a transverse section of the cylinder of a single-cylinder internal combustion motor and the throttling device for the air which forms a portion of the motive-agent mixture.

Fig. 6 is a diagrammatic elevation illustrating a method of applying my inventive idea to a multi-cylinder engine employing a carburetor.

Fig. 7 is a central vertical section of the actuating device for the throttle of the carburetor.

Fig. 8 is an elevation of a carburetor with actuating device shown in Fig. 7 applied thereto.

The construction illustrated in said drawings is substantially as follows:

The actuating member of this equipment consists of a valve 1 adapted to be actuated by fluid under pressure so as to cause a release of a portion of said fluid to actuate the regulating means; said fluid is preferably the compressed air in the receiver—not shown—into which the compressor is discharging. This valve 1 is fully shown and described in the Letters Patent previously designated, but briefly described, it comprises the following details—reference being especially to Fig. 2. The closure or cap 2 of the valve body is provided with an inwardly-extending tubular boss 3, the inner open end of which is adapted to form a seat for the valve 4: said valve 4 consists of a cup, the rim or flange 5 of which surrounds said boss 3, so as to be movable longitudinally thereon: the inner bottom wall of said valve is adapted to seat closely upon said inner or open end of said boss. Surrounding said valve 4 is an annular chamber 6, the lower wall of which is formed into a seat 7 for the seating of the outer face of said valve 4. Bearing against said outer face of said valve is a plunger 8 which is pressed in the direction of or against said valve by a compression spring 9, so as to hold said valve into contact with the seat of said tubular boss 3,

which is the normal seating position. The lower end of said spring bears upon the longitudinally-adjustable screw 10.—Fig. 3—whereby the degree of pressure whereat said 5 valve is actuatable, may be regulated as required. The stem of said plunger 8 extends through said screw 10, and is thus securely guided.

The cap 2 is provided with a pipe tap 11 10 for the insertion of a pipe 12, which leads to a supply of fluid under pressure, as previously stated. A pipe-tap 13 pierces the outer wall of said annular chamber 6 for the reception of a pipe 14 communicating with 15 the unloader of the compressor and the throttle of the engine. The flange 5 of valve 4 is provided with ports 5' for the passage of air from pipe 12 to pipe 14 when said valve 4 is in the position shown in Fig. 2.

20 The throttling equipment provided for a gas engine comprises a gas throttle 15 and an air throttle 16. The throttle 15 may be any of the well-known forms of centrifugal governors such as have heretofore been com- 25 monly used for regulating the supply of fuel gas to a gas engine. As heretofore employed, however, this form of governor has been used to regulate the gas supply only, and some suitable form of manually oper- 30 ated valve is used to regulate the air supply. When starting the engine said air valve is opened to a degree which will permit the passage of the required amount of air to produce, under average conditions, the 35 right fuel proportions of gas and air. If, however, the air pipe leading to the engine is properly proportioned, a valve for same is often dispensed with and the proper proportion of gas to make a suitable fuel mix- 40 ture under average conditions is regulated by a gas cock as 17, shown in Fig. 1. In such an arrangement, the volume of air supply remains constant while the quantity of 45 gas is constantly being varied by the action of the governor valve 18 and for this reason such a method of governing an internal combustion engine is neither so economical nor so efficient as it should be.

Incidentally to the production of a co- 50 ordinated regulating device of high efficiency, I have devised throttling means for both the air and the gas which form the fuel mixture, and whereby the relative proportions of these elements is caused to re- 55 main constant. Said gas throttle is, as previously stated, any suitable governor of the centrifugal type, as indicated at 19 in Fig. 1. The throttle for the air supply com- 60 prises a body 16, having an inner chamber 20 therein, with two passages 21, 21, sub- stantially such as are usually employed for cooperation with a balanced valve.

For cooperation with said passages 21, I provide the discs 22, which are mounted 65 upon the vertically movable stem 23. The

upper end of said stem 23 is attached to a lever 24, having, as a fulcrum at one end thereof, the link 25, which in turn is pivoted to the lug 26, carried by said body 16. To the other end of said lever 24 is connected the lower end of a reach-rod 27, the upper end of which is connected adjacent to one end of the lever 28; the other end of said lever 28 is connected to the lever shaft 29 of the centrifugal governor. 70

Mounted upon the throttle-body 16, is a cylinder 30 which carries a piston 31 supplied with a plunger or stem 32, which is positioned in axial alinement with said disc-stem 23. Beneath said piston 31 is a compression spring 33 which serves to yieldably retain said piston at the upper limit of its travel, and to return it thereto as required. The upper end of said piston is supplied with a packing member 34 which adapts it to be fluid-actuated in the downward direction in opposition to said spring 33. Pipe 14 leads from the actuator valve 1 into said cylinder 30 above said piston 31. The purpose of said pipe connection between said actuator valve and said cylinder 30 will be presently set forth, but before proceeding with this description, it is pointed out that all regulative action imparted to valve 18 by the centrifugal elements of the 95 governor, is communicated to the discs 22, through said lever 28, rod 27, lever 24 and stem 23, which produces a regulation of the air element of the fuel coordinate with and corresponding to the regulation of the gas 100 supply, thus serving to keep the relative proportions of these elements constant regardless of the total volume thereof, or the fact that they may enter the engine cylinder through separate ports especially as 105 shown in Fig. 5, in which 17' indicates the gas admission port to the cylinder and 16' indicates the air admission port.

The precise form of the air compressor unloader used with my coordinated regulat- 110 ing device is immaterial except for the sake of sufficiency of this specification.

I have shown in Fig. 4 a form of unloader that is well adapted to the purpose in view. The form of unloader here shown is applied to the intake valve of the compressor, and when unloading takes place this valve is held open and air both enters at and regurgitates therethrough, so that no new supply of air is taken into the compressor cylinder, 115 and consequently discharge of compressed air into the receiver ceases for the time being. The unloader here shown is, per se, not new, but enters into my invention as an element in a novel combination, hence it will 120 be only briefly described. The inlet valve proper is indicated in Fig. 4 by the ordinal 35, which is yieldably retained upon its seat by the springs 36: a stud 37 passes through the valve seat 38 and valve keeper 39 to se- 125 130

ure them in the assembled position; the upper end of this stud projects above said seat, and a valve lifter 40 is mounted and longitudinally movable thereon: a compression spring 41 holds said lifter normally out of contact with said valve 35. The valve-cover 42 carries a cylinder 43, in which is a piston 44, the lower end of which is bifurcate and the two legs thereof rest upon the adjacent 10 end of the valve lifter 40. Said piston 44 is also supplied with a packing 45 to adapt it to fluid actuation. Actuator pipe 14 leads into said cylinder for the admission of fluid released by the actuator 1.

15 It will readily be understood that the actuator pipe 14 whereby communication is effected between the actuator valve 1, cylinder 30 and cylinder 43 is the means whereby coordinate regulation between the unloader 20 and the throttling device is secured.

Briefly set forth, the operation of this construction is as follows: When the air in the air receiver into which the compressor is discharging (or any other suitable pressure 25 source) has reached a predetermined maximum limit, the actuator valve is caused, as aforesaid, to release a portion of said air which passes through the actuator pipe, simultaneously to the throttle cylinder 30 30 and to the unloader cylinder 43, and thus as the compressor is unloaded, the fuel supply to the engine is so reduced as to cause the speed of the engine to be lowered to a minimum. It should be noted that, when unloading takes place, the function of the fuel throttling means is reversed, in the following respects. Normally, the centrifugal 35 governor actuates both the gas valve 18, and the air valves 22, but when stem 23 is forced 40 downward by the piston 31, or its plunger, this actuation is transmitted to the valve 18, and causes a diminution of the gas supply in excess of that which should be normally 45 caused by the governor, as this normal diminution would be only such as to keep the speed of the engine constant, whereas, the action of my regulating means is such as to materially reduce the speed of the engine 50 during the interval when there is no available work being done.

A further novel and valuable function of this fuel throttling means is brought into action in case of breaking of the driving belt 46, in which case pulley 47 will drop, 55 causing a corresponding movement of the cam 48, and an actuation of the emergency lever 49, which is fixed to the shaft 29; this will cause a corresponding action of levers 28 and 24, which will cause the discs 22 to 60 close the air throttle 16. It sometimes happens that, in such an emergency as this, the valve 18 in the throttle 15 will fail to act, and in such a case the air throttling means becomes a valuable safety device.

65 A plurality of eyes 50, in the levers 24

and 28 provide for the necessary actuating adjustments.

I provide for applying my regulating equipment to a multi-cylinder engine in the manner illustrated in Figs. 6, 7 and 8. The 70 equipment here illustrated comprises the actuator valve 1, which is here shown in an inverted position, as compared with that shown in the preceding views, since it is immaterial which position is employed.

75 In this class of engines a carburetor—Fig. 8—is employed, to which I apply a throttle lever 51. An actuating device is provided for said lever 51 constructed as shown in Fig. 7. This actuating device comprises a 80 cylinder 52, carrying a piston 53, with an upwardly-extending stem 54, which projects through the top of said cylinder. Bearing upon the top of said piston is a compression spring 55 which yieldably retains said piston 85 and its stem in the lowermost position as illustrated. Said cylinder is provided with attaching lugs 56 whereby it is attached to a carburetor, as shown in Fig. 8, with the extremity of said stem 54 in contact with, 90 or in suitable juxtaposition to, said throttle lever 51.

95 When released air passes through pipe 14 it enters the unloader cylinder 43, where it performs the function previously set forth: Said released air simultaneously enters the throttle cylinder 52, and forces piston 53 upward and stem 54 correspondingly actuates lever 51 so as to partially close the throttle valve of the carburetor, thereby reducing the speed of the engine.

100 I claim the following:

1. Coordinated regulating means for an internal combustion engine and an air compressor driven thereby, comprising in combination, throttling means for the motive agent of said engine, an unloading device for said air compressor, and means coordinately actuating said throttling means and said unloading device at a predetermined 110 stage.

2. Coordinated regulating means for an internal combustion engine and an air compressor driven thereby, comprising in combination, throttling means for the motive 115 agent of said engine, an unloading device for said air compressor, and automatic means coordinately actuating said throttling means and said unloading device at a predetermined stage.

3. Coordinated regulating means for an internal combustion motor and an air compressor driven thereby, comprising in combination, a valve adapted to release an actuating agent at a predetermined stage, throttling means for the motive agent for said motor actuated by said actuating agent, and an unloader for said compressor also actuated by said agent, and means causing the coordinate actuation of said throttling 125 and unloading device.

130

means and said unloading device by said agent upon said release thereof.

4. Coordinated regulating means for an internal combustion engine and an air compressor driven thereby, comprising in combination, a valve adapted to be actuated by a fluid under pressure so as to cause a release of a portion of said fluid, means for regulating the degree of pressure whereat said valve is actuatable, throttling means for the motive agent of said engine, actuatable by said released fluid, an unloader for said compressor also actuatable by said released fluid, and means causing said actuation of said throttling means and said unloader to be coordinate.

5. Coordinated regulating means for an internal combustion engine and an air compressor driven thereby, comprising in combination, a valve adapted to be actuated by fluid under pressure and provided with means for the release of a portion of said air during said actuation, means for varying the degree of pressure whereat said valve is actuatable, adjustable throttling means for the motive agent for said engine actuatable by said released fluid, an unloader for said compressor also actuatable by said released fluid, and means causing the coordination of such actuation of said throttling means and said unloader.

6. Coordinated regulating means for an internal combustion engine and an air compressor driven thereby comprising in combination, an unloader for said compressor, fuel-throttling means for said engine and means co-ordinating the unloading function of said air compressor and the throttling function of said fuel-throttling means, in such manner that the speed of said engine is reduced when said air compressor is unloaded.

7. Coordinated regulating means for an internal combustion engine and an air compressor driven thereby comprising in combination, an unloader for said air compressor, a throttle for the fuel of said engine arranged to maintain a normal speed of said engine, and means arranged to actuate said fuel-throttling means co-ordinately with the action of said unloader for the purpose of reducing the speed of said engine below normal speed, when said unloader is active.

8. Coordinated regulating means for an internal combustion engine and an air compressor driven thereby comprising in com-

bination, an unloader for said compressor, throttling means for the fuel of said engine adapted to maintain the desired normal speed of said engine under normal power requirements therefrom, and means adapted to automatically actuate said throttling means for the purpose of reducing the speed of said engine co-ordinately with the unloading action of said unloader.

9. Coordinated regulating means for an air compressor and an internal combustion engine arranged to drive said compressor, comprising an air compressor provided with an unloader arranged to arrest the delivery of air from said air compressor at a determined stage of pressure of the air so delivered, in combination with an internal combustion engine arranged to drive said air compressor, throttling means for the fuel supplied to said engine, means associated with said throttling means active synchronously with the action of said unloader whereby said fuel supply to said engine is reduced when said unloader is active, and means restoring said throttling means to its normal fuel-admitting position, upon the discontinuance of the action of said unloader.

10. Coordinated regulating means for an internal combustion engine and an air compressor driven thereby comprising in combination, an air compressor, an unloader for said air compressor adapted to arrest the delivery of air from said air compressor at a stage of determined pressure of said air, an internal combustion engine arranged to drive said compressor, throttling means for the fuel supply of said engine arranged to maintain a desired normal speed of said engine when said unloader is inactive, a pressure-actuated valve in communication with a receiver containing compressed air delivered by said air compressor, said valve being adapted to release air from said receiver at said determined pressure, and means simultaneously delivering said released air to said unloader to actuate same into its unloading position and to said throttling means, whereby a reduction as compared with the normal amount of fuel supplied to said engine is caused during the period wherein said unloader is maintained in said unloading position.

LEON F. HOFFMAN.
